DOORSILL SEAL

Boyd E. Hornor, Jr., Fort Lauderdale, Fla.

Application June 30, 1950, Serial No. 171,322

4 Claims. (Cl. 20—68)

1

This invention relates to door sill seals of the type which are carried by the door and automatically lift responsive to the initial opening movement of the door, and automatically lower at the final closing movement of the door to engage the door sill or floor in an air or moisture tight manner, and to exclude dust, insects and vermin.

In known devices of this character, the immediate sealing means is usually a flexible strip extending across the bottom of the door, lifted by a spring which reacts against the seal at one end, and lowered by means located at the opposite end, which opposes the spring. Due to the length of the device, it is thus subjected to a twisting torque so that unless made sturdy, the edge of the sealing strip becomes longitudinally distorted and will not lie against the threshold with uniform pressure throughout, resulting in an imperfect seal. The making of the known device sufficiently inherently rigid to withstand this torque distortion increases the expensiveness of the device.

The principal object of the present invention is to provide a door sill seal of the type described, in which the torque between the spring and the lowering means which acts against the spring are at the same end of the device, so that the torque effect upon the seal is confined within a short portion of its length, avoiding the distortion above referred to.

Other objects of the invention will appear as the following description of a preferred and practical embodiment thereof proceeds.

In the drawing which accompanies and forms a part of the following specification, and throughout the figures of which the same reference characters have been used to denote identical parts:

Figure 1 is a front view in elevation showing the lower part of a door and its jambs with the door sill seal of the present invention applied thereto, an intermediate portion of the device being broken away;

Figure 2 is a horizontal section taken along the line 2—2 of Figure 1;

Figure 3 is a vertical section taken along the line 3—3 of Figure 1;

Figure 4 is a vertical section on an enlarged scale taken along the line 4—4 of Figure 1;

Figure 4a is a section taken along the line 4a—4a of Figure 1;

Figure 5 is a section similar to Figure 3, but showing the actuating pin above the axis of the spring operated member, the arrangement being

2

for a door that closes with the door sill seal trailing;

Figure 6 is a vertical section taken along the line 6—6 of Figure 5.

Referring now in detail to the several figures, and first to the group including Figures 1 to 4, inclusive, the numeral 1 represents a door, 2 and 3 being the jambs. It is assumed that the door is hinged to the jamb 3, and that the free edge 4 of the door closes against a rabbet 5 on the opposite jamb 2.

In general, a door sill seal is used in connection with the outside doors of a house. These may open either into the room as in most residences, or open toward the street, as in most public buildings to satisfy fire regulations. In either case, the door sill seal is mounted on the outside of the door, that is, the side exposed to the weather. Consequently, in the closing movement of a residence door the door sill seal leads, while in the case of a door which opens to the street, the door sill seal trails. The group of Figures 1 to 4 represent the door of a residence in which, in closing, the door sill seal leads. The door sill seal is equally adapted to inside doors for temperature controlled rooms or where dust exclusion is of prime importance, etc. The door sill seal comprises a casing 6 which extends substantially the full width of the space between the door jambs, being just sufficiently shorter than said space to clear the jambs in the arcuate movement of the door. The casing comprises a hollow cylindrical portion 7 and a flat flange 8 integral therewith and tangent thereto, having facilities such as the screws 9 for attaching the door sill seal to the lower part of the door. The cylindrical portion serves as a seat or bearing for a tube 10, which fits rotatably within said casing. The cylindrical portion 7 is provided with a slot 11, extending thereacross, the width amplitude of said slot being about 90° of the inner circumference of said cylindrical member, said slot being on the forward side of said member, beginning substantially at its horizontal axial plane and extending downwardly.

The tube 10 has a relatively narrow slot 12 extending its full length and in registry with the slot 11 throughout the range of arcuate movement of said tube, as will be explained.

Referring to Figure 2, it is seen that the end of the tube 10 which is adjacent the hinge end of the door, that is, adjacent the jamb 3, is closed by means of a cap 13, which may be fixed in place by any suitable means. It is shown having a lug 29 at one point which keys into a cor-

responding slot 30 formed in the tube 10. The opposite end of the tube 10 is closed by a cap 14, secured in the same manner as the cap 13, and the adjacent end of the casing is closed by a cap 15. The cap 15 has a peripheral lug 31 which projects into the slot 11 fitting the width thereof. A flexible strip 16 of any suitable material, such as rubber, neoprene, etc., has one edge 17 inserted in the slot 12. Said inserted edge extends the full length of the tube 10, the caps 13 and 14 being slotted as at 28 to receive said edge, but the strip 16 extends laterally beyond said edge as at 18 and 19, so as to be coextensive with the overall length of the casing 6. The width of the flexible strip 16 is such that when it is in sealing relation to the floor or threshold, it is bent out of its normal position of repose and assumes a deformed shape, as shown particularly in Figure 4, pressing the floor or threshold with a uniform pressure from end to end.

A pin 20 is fixed within the tube 10 adjacent one end thereof, extending outwardly beyond the casing 6 through the cap 14 near its periphery. This pin is designed to engage the stop plate 21, in the final closing movement of the door, which is attached to the back wall of a recess 22 formed in the rabbet of the jamb. The pin 20 is cut with the rabbets as shown in Figure 6, forming a shoulder 33 that lies adjacent the inner side of the cap 14, a shoulder 34 which bears against the end wall of the tube 10, and a shoulder 35 which lies adjacent the outer side of the cap 15. The pin so constructed provides stops to prevent end movements of the parts which lie contiguous to its several shoulders, and the outer end of said pin is at the maximum radial distance from the axis of the tube 10, giving it optimum mechanical advantage in opposing the bias of the spring 25.

A post 23 is fixed to the center of the cap 15 and projects inward axially of the tube 10, passing freely through a central aperture in the cap 14. A spring support 24 extends diametrically across the tube 10, having its ends set in apertures in said tube. A spiral spring 25 has its ends respectively anchored to the post 23 and spring support 24, the direction of twist of said spring being such as to cause it to react between the fixed post and the movable spring support to rotate the tube 10 in such a direction as to tilt the flexible sealing strip 16 in an upward direction, its uppermost position being indicated in broken lines in Figures 3, 4 and 5.

The cap 15 has the arcuate slot 26 through which the pin 20 passes, providing play for the movement of said pin as the tube 10 rotates within the casing.

Figure 3 shows the pin and slot located in the lower arc of the path of oscillation of the tube 10 and adapted to be moved from a low to a high position in said arc when the door is moved in the direction of the arrow to close it. Obviously, as the pin 20 moves up, the tube 10 rotates in a clockwise direction, lowering the sealing strip from the broken line to full line position shown in Figure 3.

Figure 5 shows the pin 20 and slot 26 in the upper arc of the end of the casing 6. This figure depicts a door which opens outwardly to the street. The arrow indicates its closing direction. It is obvious that, starting with the pin 20 in the lower end of the slot, it will collide with the stop plate 21 as the door closes, and be raised upwardly as it traverses the arcuate slot. This rotates the tube 10 in a counterclockwise direction and brings the sealing strip 16 into close engagement with the floor. In this case the stop plate 21 is set out from the door engaging surface of the jamb on a block 27, instead of being at the back of a recess as in Figures 1 to 4.

Due to the fact that the operating pin 20 is at the same end of the tube 10 as the spring 25, only a very small portion of the length of said tube 10 will be subjected to torsional stress, and consequently, the tube 10 may be counted upon to maintain its untwisted cylindrical condition, keeping the lower edge of the sealing strip 16 rectilinear and causing it to press uniformly against the floor or threshold from end to end.

It will be understood that the pin 20 rotates the tube 10 in a contra direction with respect to the bias of the spring 25, so that it is not the spring which presses the flexible sealing strip 16 against the floor or threshold, but the inherent resiliency in the sealing strip, urged by the pressure of the pin 20.

While I have in the above description disclosed what I believe to be a preferred and practical embodiment of the invention, it will be understood by those skilled in the art that the specific details of construction and arrangement of parts, as described, are by way of illustration and not to be construed as limiting the spirit or scope of the invention.

What I claim as my invention is:

1. Door sill seal comprising a casing having means for securing it widthwise against a door, said casing having a cylindrical bore and a longitudinal slot opening into said bore, a tube rotatably fitting within said bore having a longitudinal flexible sealing strip secured thereto extending through the slot in said casing, a pin projecting longitudinally from one end of said tube, rotatable therewith and extending beyond the adjacent end of said casing, a closure for said end of the tube having a central aperture and a slot at its periphery forming a passage for said pin, a closure for the adjacent end of said casing nonrotatably secured to said casing by a lug on one interdigitating with a slot in the other, said last named closure having an arcuate slot through which said pin extends and in which it plays, a post fixed to said casing closure at the center extending through the aperture in said tube closure and axially within said tube, a spring support fixed within said tube at a distance from said closures, a helical spring about said post anchored at its respective ends to said post and said spring support under axial tension, normally biased to react against said post to rotate said tube in a direction to tilt said sealing strip upward, said pin and slot being so angularly displaced with respect to the circumference of said tube as to rotate the latter in a direction contra to the bias of said spring when said pin is moved through said slot in contacting the door jamb as the door is closed, for tilting the flexible strip downward.

2. Door sill seal as claimed in claim 1, the jamb contacting portion of said pin being offset in a radial direction away from the axis of rotation of said tube, thereby increasing the mechanical advantage of said pin in opposing the bias of said spring.

3. Door sill seal comprising a casing having means for securing it widthwise against a door, said casing having a cylindrical bore and a longitudinal slot opening into said bore, a tube rotatably fitting within said bore having a longi-

tudinal flexible sealing strip secured thereto extending through the slot in said casing, a pin projecting longitudinally from one end of said tube rotatable therewith and extending beyond the adjacent end of said casing, a closure for said adjacent end of said casing nonrotatably secured to said casing by a lug on one engaging with a slot in the other, said closure having a fixed post at its center coaxial with said tube and extending thereinto, a support for a spring fixed within said tube longitudinally spaced from the inner end of said post, a helical spring within said tube anchored at its respective ends to said post and support under axial tension, normally biased to react against said post to rotate said tube in a direction to tilt said sealing strip upward, said closure having an arcuate slot concentric to said post through which said pin extends and within which it plays, said slot being so positioned as to present said pin in position to rotate said tube contra to the bias of said spring when said pin contacts the door jamb as the door is closed, for tilting the flexible strip downward.

4. Door sill seal as claimed in claim 3, the jamb contacting portion of said pin being offset in a radial direction away from the axis of rotation of said tube, thereby increasing the mechanical advantage of said pin in opposing the bias of said spring.
